ABSTRACT

A hinge mechanism securing a panel to a case, which mechanism provides for rectilinear and pivotal movement of the panel relative to the case.

5 Claims, 9 Drawing Figures

FIG-7

FIG-8

FIG-9

HINGE MECHANISM

BACKGROUND OF THE INVENTION

Certain electrical instruments comprise a case carrying electrical components and circuitry and a panel which has printed thereon technical information pertinent to the particular instrument. The panel is recessed from an open end of the case and normally covers the components and circuitry which are supported on the base of case. The panel is latched in such normal position and is secured to the case by hinge means whereby the panel may be rotated into an upright position affording access to the contents of the case by the user. Various latching and hinge arrangements are available for the stated purposes but these involve a relatively large number of separate parts and require costly assembly procedures.

A hinge mechanism made in accordance with this invention is of simple, economical construction and is assembled quickly at minimum cost.

SUMMARY OF THE INVENTION

The hinge mechanism comprises a shaft carried by the panel and having end portions supported by flat surfaces which afford limited lateral displacement of the shaft. Spring means, positioned between an edge of the panel and an inner wall of the case, maintain a pressure on the panel and tend to displace the panel, linearly, from such inner surface. This pressure serves to retain an opposite end portion of the panel in a slot provided at the opposite inner wall of the case, thereby to retain the panel in the normal, latched position. Linear displacement of the panel against the action of the spring means, unlatches the panel so that it can be rotated about the shaft to an upright position.

An object of this invention is the provision of an improved hinge mechanism connecting a panel to a case, which mechanism permits pivotal and rectilinear movement of the panel with respect to the case.

An object of this invention is the provision of a hinge mechanism connecting a panel to a case, which mechanism comprises means for rotating the panel between an upright position and a normal position substantially parallel to the base of the case, and spring means which serves to maintain the panel in the upright position and to press the panel into a latching arrangement when the panel is in the normal position.

The above-stated and other objects and advantages of the invention will become apparent from the following description when taken with the accompanying drawings. It will be understood, however, that the drawings are for purposes of illustration and are not to be construed as defining the scope or limits of the invention, reference being had for the latter purpose to the claims appended hereto.

BRIEF DESCRIPTION OF THE DRAWINGS

In the drawings wherein like reference characters denote like parts in the several views:

FIG. 1 is a top plan view showing a panel which is secured to a case by a hinge mechanism made in accordance with this invention, the panel being shown in the normal position;

FIG. 2 is a fragmentary end elevational view showing the panel in the raised position;

FIG. 3 is an enlarged, fragmentary, top plan view showing the upper left corner of the case and panel as viewed in FIG. 1;

FIG. 4 is similar to FIG. 3 but with the panel removed from the case;

FIG. 5 is an enlarged, isometric view of one of the springs;

FIG. 6 is an enlarged cross-sectional view taken along the line 6-6 of FIG. 1;

FIG. 7 is an enlarged cross-sectional view taken along the line 7-7 of FIG. 3;

FIG. 8 is an enlarged cross-sectional view taken along the line 8-8 of FIG. 3; and

FIG. 9 is similar to FIG. 7 but showing the panel in the raised position.

DESCRIPTION OF PREFERRED EMBODIMENT

Referring to FIGS. 1 and 2, the panel 10 is secured to the case 11 by a hinge mechanism affording rectilinear and pivotal movement of the panel relative to the case. The hinge mechanism comprises a pair generally U-shaped springs 12 and 12', see spring 12 shown in FIG. 5. One leg of each spring is in engagement with the inner wall of the case, the other leg of each spring being in engagement with a side edge of the panel when the panel is in the normal position as shown in FIG. 1. Aligned slots 13, 13' are formed in the end portions of the panel and the corner portions of the panel are offset at right angles to the plane of the panel, thereby forming tabs 14 and 14' which extend downwardly into the case as viewed in FIG. 1. A shaft 15 passes through aligned clearance holes formed in these tabs and the end portions of the shaft extend under the rectangular plate 16, 16', which plates are secured in fixed positions by the fastening screws 17, 17', respectively. A more detailed description of the construction and operative relationship of the various components forming the hinge mechanism will be given below. It is here pointed out that the springs 12, 12' provide a biasing force tending to displace the panel toward the projection 18 extending from the inner wall of the case. Preferably, the case is made of a suitable plastic and the projection 18 is formed integrally therewith. Referring to FIG. 6, it will be seen that the projection 18 has a relatively thick-walled lower portion 19 and a tapered upper portion 20, which portions terminate in a slot 21 accommodating the edge portion of the panel 10. As shown in FIG. 6, the panel is in the normal position and is latched in such position by the pressure exerted against the opposite side of the panel by the springs 12, 12', FIG. 1. As will be described, below, the hinge mechanism is so arranged that the panel can be displaced to the left, as viewed in FIGS. 1 and 6. The range of such panel displacement is sufficient to permit the right side edge of the panel to clear the overhanging portion of the projection 18, whereby the panel can be rotated in a counterclockwise direction about the shaft 15, FIG. 1, to the raised position shown in FIG. 2. A finger hole 22 is provided in the panel to facilitate such linear displacement of the panel by the user.

The configuration of the spring 12 is shown in FIG. 5, such spring having a relatively long arm 23 and a short arm 24, the latter arm including an integral, laterally-extending tab 25. The other spring 12', FIG. 1, is similar to the spring 12 except that the laterally-extending tab of the spring 12' extends in a direction opposite to that of the tab 25 of the spring 12.

Reference now is made to FIG. 3 which is an enlarged, top plan view showing the upper left corner of the case and panel as viewed in FIG. 1. The spring 12 has its base portion positioned within a pocket formed on the base of the case 10. The long spring arm 23 is in engagement with the side edge of the panel 10, while the short spring arm 24 is in engagement with the inner wall of the case. The spring tab 25 extends under the rectangular plate 16 which is secured in fixed position by the fastening screw 17 threaded into a hole formed in an integral boss formed in the corner of the case.

The pocket for the spring 12 is shown in FIG. 4 which is similar to FIG. 3 but with the panel, spring, rectangular plate and fastening screw removed. The spring pocket, identified by the numeral 33, is formed by the integral ridges 26, 27 and 28, and the encompassed portion of the inner wall of the case. These ridges extend upwardly a relatively short distance from the case base, thereby to retain the spring in a relatively fixed position while not interfering with the required spring action. Also visible in FIG. 4, is the integral, corner boss 29, said boss having a flat surface 30 which supports the rectangular plate 16 shown in FIG. 3. A threaded hole 31 formed in this surface of the boss receives the fastening screw 17 shown in FIG. 3. The corner portion of the boss is recessed to provide a flat surface 32 which supports the shaft 15 shown in FIG. 1.

FIG. 7 is a cross-sectional view taken along the line 7—7 of FIG. 3. This view shows the height of the ridge 28 of the spring pocket, the downwardly-dependant tab 14 of the panel 10, and the shaft 15 which passes through a clearance hole formed in said tab. The end portion of the shaft is supported by the flat surface 32 which forms the bottom wall of the recess formed in the boss 29. It will be apparent that the shaft will roll along the surface 32 when the panel 10 is displaced to the right and that the spring exerts a pressure against the side edge of the panel, thereby to retain the panel in the normal, latched position, as has been described hereinabove with reference to FIG. 4.

FIG. 8, which is a cross-sectional view taken along the line 8—8 of FIG. 3, shows the rectangular plate 16 overlying the shaft 15 and the tab 25 of the spring, said plate being secured to the boss 29 by the fastening screw 17. The plate 16 serves to retain spring in the pocket 33 and to maintain the shaft in proper assembled position in the case.

FIG. 9 is similar to FIG. 7 but showing the panel 10 in the raised position, in which position the spring arm 23 is in engagement with the upper surface of the panel. Under this condition, the spring exerts a force against the panel to retain the panel in the raised position. To return the panel to its normal position, it is forcefully rotated in a clockwise direction about the shaft 15 until the free side edge of the panel engages the tapered wall of the projection 18, see FIG. 6. A

downward pressure now applied to the panel results in a displacement of the panel and shaft in the direction of the spring. When the edge of the panel is aligned with the slot 21, FIG. 6, the spring action causes the panel to snap into the slot.

While a detailed description has been given with specific reference to the spring 12 and the components associated therewith, the spring 12' and its associated components are of similar construction and assembly, whereby the two springs act in unison as the panel is moved from one to the other position.

I claim:

1. A hinge mechanism securing a panel to a case and comprising,
  - a. a pair of fixed supports positioned at two internal, adjacent corners of the case, said supports having flat surfaces lying in a plane spaced from and substantially parallel to the plane of the base of the case,
  - b. a shaft rotatably carried by the panel along one edge thereof, said shaft having end portions supported on the said flat surfaces and said shaft having a diameter less than the length of the flat surfaces taken in a direction normal to the shaft axis,
  - c. means limiting lateral displacement of the shaft in a direction away from the said flat surface,
  - d. spring means disposed between an inner wall of the case and the said one edge of the panel, said spring means normally applying pressure to the panel in a direction away from the said inner wall of the case, and
  - e. latching means disposed at the opposite inner wall of the case for securing the panel in a plane substantially parallel to that of the base of the case.
2. The invention as recited in claim 1, wherein the corner portions of the panel are offset at substantially right angles to the plane of the panel, and wherein the said shaft passes through aligned holes formed in the offset portions of the panel.
3. The invention as recited in claim 1, including means forming a pair of pockets on the base of the case, and wherein the said spring means comprises a pair of generally U-shaped springs having base portions disposed in said pockets.
4. The invention as recited in claim 3, wherein the said pockets are proximate to the said fixed supports, and wherein each spring includes a tab disposed under the said means limiting lateral displacement of the shaft.
5. The invention as recited in claim 1, wherein the said latching means comprises a projection extending inwardly of the case, said projection having a tapered portion terminating in a slot which receives the opposite edge of the panel.
